UNITED STATES PATENT OFFICE.

TOBIAS WEBER, OF LOS ANGELES, CALIFORNIA.

TRAILER COUPLING.

1,426,134.

Specification of Letters Patent. Patented Aug. 15, 1922.

Application filed March 7, 1922. Serial No. 541,796.

To all whom it may concern:

Be it known that I, TOBIAS WEBER, a citizen of the United States, and resident of Los Angeles, in the county of Los Angeles and State of California, have invented new and useful Improvements in a Trailer Coupling, of which the following is a specification.

This invention relates to a trailer coupling of the eye and hook type, such as is disclosed in United States Letters Patent 1,375,266, granted to me April 19, 1921, and pertains particularly to a catch for holding the hook guard.

It is the primary object of this invention to provide a catch which will act as a detent to hold the guard in open or closed position; and further to provide a construction such that the catch may be manually adjusted so that it will not lock the guard. Another object of this invention is to provide a construction of the character described in which the catch may be set so as not to lock the guard, and opening of the guard, will cause the catch to be set for locking it in closed position.

These objects together with other objects and corresponding accomplishments are obtained by means of the embodiment of my invention illustrated in the accompanying drawing, in which:

Fig. 1 is a perspective view of a hook, with a portion of the catch housing broken away to better show the construction; and Fig. 2 is a side elevation with part in section showing the complete hook.

Referring more particularly to the drawing, a base or attachment plate is indicated by 3. This plate is provided with bolt holes 40 to receive bolts 4, which are passed through the body of the wagon indicated by 5 in Fig. 2, and through a yoke plate 6 resting against the inside of the body. Outstanding from the base are ears 7 joined at the 45 front by a bridge 8 forming a bracket. The bridge serves as an abutment for the swinging guard which is pivotally mounted in the bracket. Extending from one side of an ear 7 is a catch housing 9. Disposed below the 50 bracket, which overhangs it, is a hook 10.

Mounted in bearings on the ears is a pivot shaft 11. The pivot shaft is bent laterally at one end to form a handle 12, whereby it can be grasped and moved. A guard 14 is 55 formed with a sleeve 15 at its forward end. The sleeve is bored and receives the pivot

shaft 11. The guard and shaft are secured together by means of a set screw 16 so that the relative angle between the two may be adjusted to suit the convenience of the operator. Guard 14 is of fan shape and has an extension 17 to register with the end of the hook 10. The sleeve 15 is formed with a stop 18 for engaging the bridge 8 and limiting the movement of the guard to its open 60 position. Formed in the guard and extending therethrough are holes 19 and 20. Disposed intermediate holes 19 and 20 and adjacent hole 20 is a lug 21. Lug 21 forms a tappet for a purpose later described.

Slidably and rotatably disposed in the housing 9 is a latch pin 22. The latch pin is provided with collar 23, and a reduced portion 24 is provided to engage and hold the guard. A spring 25 is disposed over the 65 pin 22 between the collar 23 and a shoulder 26 in the housing. The outer end of the pin is provided with a head 27 which may be conveniently grasped. Extending from the end of the latch pin is an eccentrically disposed lug 28 for engagement by the tappet 21. Mounted upon the latch pin and extending laterally, is a stop pin 29. The stop pin is arranged to rest against the end of the housing and limit the position to which 70 the spring 25 may move the pin. The outer end of the housing is constructed to form three steps 30, 31, and 32. When the stop pin 29 rests against step 30, the latch pin is 75 in such position that it will not enter either the hole 19 or 20 and eccentric lug 28 is out of the path of the tappet 21. When the stop pin 29 rests against the step 31, the pin 22 is 80 so disposed that eccentric pin 28 is in the path of tappet 21. Upon swinging the guard into open position the tappet will engage eccentric pin 28, thereby turning latch pin 22 so that stop pin 29 may rest against step 32. In this position, the latch pin will be forced 85 into either hole 19 or 20 when in register 90 therewith, and thus lock the guard.

An eye for attaching to the hook is indicated by 33, and in the drawing, the eye is shown in position on the hook 10 with the guard in closed position. The stop pin is 95 disposed against step 31 with the eccentric pin 28 in the path of tappet 21. The weight of the guard is sufficient to hold the latter in its closed position. If it is desired to remove the eye from the hook, handle 12 is 100 grasped and by pressing upon the same the guard may be lifted. When the guard

reaches its upper position, tappet 21 engages eccentric 28, turns latch pin 24 so that stop pin 29 registers with step 32.

Latch pin 24 will drop into hole 20 and 5 will hold the guard in open position. To release the guard, catch 22 is withdrawn from the hole 20 allowing the guard to drop. The catch is then turned so that stop 29 rests against step 31. Suppose the eye 33 is to be 10 engaged with the hook, the eye is forced against the extension 17. This raises the guard so that tappet 21 engages the eccentric 28 and turns the catch. In practice the weight of the guard is such that it will not 15 be raised sufficiently by impact of the eye for the lower hole to be engaged by the catch. When the guard drops, the spring 25 forces the catch into hole 19 thereby locking the guard closed. If it is desired to set the 20 catch so that it will not operate, the catch is turned so that stop 29 rests against step 30.

What I claim is:

1. In a coupling the combination with a hook and a pivoted guard for closing the 25 mouth of said hook, of locking means to positively hold said guard in a predetermined position relative to said hook, said

locking means comprising a latch, means to manually set said latch in unlocking position, and means operated by opening of the 30 guard to release said latch from unlocking position.

2. In a coupling the combination with a hook and a pivoted guard for closing the mouth of said hook having a hole for a latch 35 pin to lock the guard in a predetermined position of a latch pin and a spring mounted so that the spring will tend to force said pin into said hole, and means to limit the movement of said pin into said hole so that it may 40 be set in locking or unlocking position, and means operated by opening of the guard to release said latch from unlocking position.

3. In a coupling, the combination as specified in claim 3 characterized by the guard 45 having a tappet and an eccentric pin on said latch whereby said latch pin will be rotated from unlocking to locking position upon engagement by said tappet when said guard is moved in one direction.

In witness that I claim the foregoing I have hereunto subscribed my name this 17th day of February, 1922.

TOBIAS WEBER.
